UNITED STATES PATENT OFFICE.

WILLIAM P. REAVES, OF GREENSBORO, NORTH CAROLINA.

ASTIGMATIC AND VISUAL ACUITY APPARATUS.

Application filed June 30, 1920, Serial No. 393,143. Renewed February 21, 1923.

To all whom it may concern:

Be it known that I, WILLIAM P. REAVES, a citizen of the United States, residing at Greensboro, in the county of Guilford and 5 State of North Carolina, have invented certain new and useful Improvements in Astigmatic and Visual Acuity Apparatus; and I do hereby declare the following to be a full, clear, and exact description of the 10 same, reference being had to the accompanying drawings, forming part of this specification.

This invention relates to devices used by oculists and opticians for determining the 15 amount and direction of astigmatism in the eyes of their patients, and has for its principal object the provision of a device of this character which will save material time in eye testing, because of the ease and convenience by which the patient is enabled to 20 inform the oculist as to the exact position of the blurred field of vision.

A more detailed object of the invention lies in the provision of an indicator adapted to sweep over the semi-circle of radial 25 lines common in optical charts, whereby the patient whether illiterate or not, may readily inform the oculist by word or motion of hand when the arrow points to the most 30 distinct lines.

Other and further objects of the invention less important than those heretofore mentioned, will be apparent from the following description, and such details will 35 be distinctly specified in the claims following such description.

Figure 1 represents an end view of my device as seen by the patient;

Figure 2 is a similar view but with the 40 indicator and chart removed;

Figure 3 is a side elevation of my device with the side wall removed;

In its preferred form my device consists 45 of a metal or wooden box 10 having an open front, which is closed by a pane of translucent glass 11 of the usual opalescent or milky color so that the mechanism within the box cannot be observed by the patient. A further advantage of this color of glass 50 is to relieve the eye of all strains incident to the use of clear glass which would not diffuse the light in an even manner.

On the glass pane 11 is delineated a plurality of radial lines 12 five degrees apart 55 forming together a semi-circle each third line of which has a numeral 13 to denote

the number of degrees from the zero mark 14. Centrally of these radial lines are two letters 16 indicating the next higher chart, and beneath the semi-circle are a series of 60 letters 17, the thickness of each of which is exactly equal to the thickness of the radial lines 12.

The line that corresponds to the astigmatic axis of the eye of the patient will 65 after correction of any myopia or hyperopia appear clearer and more distinct to the patient than the other lines. The oculist, usually stationed beside the patient at a distance of about twenty feet from the chart, 70 draws the indicator to this clearest appearing line in accordance with directions given by the patient by motion of the hand, or otherwise.

The oculist now neutralizes the indicated 75 astigmatism by slipping in the trial frame before the patient's eye the lens that corrects the astigmatism, when all lines will appear equally sharp and well defined. The patient can now read the row of letters 80 17 which gives the acuteness of vision of the patient.

It will be understood by those familiar with the art, that in practice the box 10 will contain two, three or four charts, for 85 example, Snellen's type

20 20 20
30 20 15 and 10'

but for convenience of illustration, the box 90 is shown with one of such charts, the others being generally similar.

Within the box and parallel to the base thereof is located a shaft 20 concentric with the semi-circular radial lines 12 and having a bearing 21 in the front glass 11, and a similar bearing 22' in the rear wall. This shaft 20 carries at a point near its rear end a wheel 23 to which is secured by any desired fastenings, such as 24, a cable 25 by means of which the wheel and therefore the shaft 20 may be rotated about its axis in opposition to the effect of a spring 22, secured at one end to the shaft 20 and by its free end to the rear wall 26 of the box. I preferably provide a stop 28 on the cord adapted to contact with a screw eye 29 to prevent excess movement of the shaft in one direction and I also provide a similar stop 30 and a corresponding screw eye 31 on the outside of the box to normally maintain the shaft in such position that the in-

5 indicator hereinafter described will point to zero degrees. In order that the cable 25 may be directed to the oculist's position, it is preferably led over a small pulley wheel 33 journaled in bearings 34 on the side wall of the box.

10 Within the box, and as near the shaft 20 as possible, I mount an electric lamp 35 or other preferred source of light in order to illuminate the figures on the front glass of the box. This lamp is preferably mounted in a socket 36 held in desired position by means of a bracket 37 secured to the lower wall by means of screws or other fastenings 15 passing through the lugs 38 of the bracket. The electric wires 39 for the lamp are connected to the terminals 40 on the outside of the box and the latter may in turn be connected to a switch located conveniently for 20 the oculist.

Secured to the shaft 20 on the outside of the box 10 is an indicator 42 having a relatively small white metal stem 43 and an enlarged arrow head 44 preferably of dull 25 black, similar to the color of the lines 12. The arrow 44, as illustrated in Fig. 1, is preferably spaced from the stem about 12 $\frac{1}{2}$ degrees so that when the arrow head 44 is directly over one of the radial lines, as for 30 example, the 90° one, the metal stem 43 will lie between the 100° mark and the 105° mark, and since such stem is white it will not affect the vision and will be practically invisible, but the arrow head itself, being 35 black, will stand out definitely on the chart.

The patient is frequently unable to denote to the oculist the exact line that appears most distinct to her vision, owing to her inability to read or decipher the degree 40 marks at the given distance, and for this purpose it is common practice for an assistant with a wooden pointer to move the pointer about a semicircle until the desired 45 position is reached. With my device the oculist, who is usually about twenty feet away, merely pulls the cable 25 and brings the arrow to the point of clearest vision with little delay and without the need of an assistant.

50 Particular attention is called to the fact that with the aid of my device the oculist is enabled to remain constantly at the side of the patient and at a distance from the chart, thus saving the very appreciable amount of 55 time that would otherwise be consumed in traveling to the chart to indicate the line and back to the patient to replace the trial glass that had been found unsatisfactory.

What I claim is:

1. In an astigmatic chart, a series of radial lines, an indicator pivoted at the center of said radial lines and having a laterally offset end spaced from the stem of the indicator so as to lie between two of the radial lines when the head of the indicator indicates another of said radial lines. 60

2. In an astigmatic and visual acuity device, a receptacle having an open end, a removable panel of translucent material, a series of radial lines or marks on said panel, a source of light within said receptacle adapted to illuminate said translucent panel and to render the radial lines visible, a shaft, an indicator on said shaft having a laterally offset headed end, the distance between the head of said indicator and the stem of said indicator being such that when the head of the indicator is in line with one of said marks that the stem will lie between two of the other marks, and means controlled by the oculist from his position beside the patient at a distance from the panel for rotating said shaft so as to bring the head of the indicator in line with a chosen one of said marks. 65

3. In an astigmatic and visual acuity device, a receptacle having an open end, a removable panel of translucent material of light color, a series of radial lines or marks on said panel spaced apart an even number of degrees said marks being of dark color to contrast with the face of the panel, a source of light within said receptacle adapted to illuminate said translucent panel and to render the radial lines visible, a support 80 for said light, a shaft supported by said receptacle and by said support and adapted to pass through said panel, an indicator on said shaft having a laterally offset headed end, the stem of said indicator being of light colored material and the head of said indicator being of dark colored material, and the distance between the head of said indicator and the stem of said indicator being such that when the head of the indicator is in line with one of said marks that the stem will lie between two of the other 85 marks. 85

4. In an astigmatic and visual acuity device, a receptacle having an open end, a removable panel of translucent material of light color, a series of radial lines or marks on said panel spaced apart an even number of degrees said marks being of dark color to contrast with the face of the panel, a source of light within said receptacle adapted to illuminate said translucent panel and to render the radial lines visible, a support 90 for said light, a shaft supported by said receptacle and by said support and adapted to pass through said panel, an indicator on said shaft having a laterally offset headed end, the stem of said indicator being of light colored material and the head of said indicator being of dark colored material, and the distance between the head of said indicator and the stem of said indicator being such that when the head of the indicator is in line with one of said marks that the stem will lie between two of the other 95 marks. 95

5. In an astigmatic and visual acuity device, a receptacle having an open end, a removable panel of translucent material of light color, a series of radial lines or marks on said panel spaced apart an even number of degrees said marks being of dark color to contrast with the face of the panel, a source of light within said receptacle adapted to illuminate said translucent panel and to render the radial lines visible, a support 100 for said light, a shaft supported by said receptacle and by said support and adapted to pass through said panel, an indicator on said shaft having a laterally offset headed end, the stem of said indicator being of light colored material and the head of said indicator being of dark colored material, and the distance between the head of said indicator and the stem of said indicator being such that when the head of the indicator is in line with one of said marks that the stem will lie between two of the other 105 marks. 105

6. In an astigmatic and visual acuity device, a receptacle having an open end, a removable panel of translucent material of light color, a series of radial lines or marks on said panel spaced apart an even number of degrees said marks being of dark color to contrast with the face of the panel, a source of light within said receptacle adapted to illuminate said translucent panel and to render the radial lines visible, a support 110 for said light, a shaft supported by said receptacle and by said support and adapted to pass through said panel, an indicator on said shaft having a laterally offset headed end, the stem of said indicator being of light colored material and the head of said indicator being of dark colored material, and the distance between the head of said indicator and the stem of said indicator being such that when the head of the indicator is in line with one of said marks that the stem will lie between two of the other marks. 110

WILLIAM P. REAVES.
